UNITED STATES PATENT OFFICE.

JAMES A. SLUSS, OF KNOXVILLE, TENNESSEE.

ADJUSTABLE MAIL-BOX SUPPORT.

Application filed April 26, 1927. Serial No. 186,753.

This invention relates to mail box supports and is particularly adapted for use along rural free delivery routes.

One object of the invention is to provide a support upon which a mail box may be mounted and swung into position where it may be easily reached by the mail carrier without leaving his automobile or other vehicle and then returned to its normal position at one side of the road.

Another object of the invention is to provide the support with an improved type of box-carrying arm and to further provide improved means to pivotally mount the box-carrying arm upon a post or standard.

Another object of the invention is to provide a mounting bracket for the box-carrying arm which may be formed from strips of metal and will be very strong and durable and not liable to be bent out of shape by the weight of the box or by rough handling.

Another object of the invention is to releasably hold the box-carrying arm in its normal position at one side of the road through the medium of a latch carried by the mounting bracket and so constructed that it may be readily moved to release the box-carrying arm so that the arm may be swung outwardly towards the mail man and re-engaged therewith when the arm is returned to its normal position.

The invention is illustrated in the accompanying drawing, wherein

Figure 1 is a perspective view of the improved mail box support;

Fig. 2 is a fragmentary view showing the latch in elevation and upper bar of the box-carrying arm or bracket in section;

Fig. 3 is a sectional view taken on the line 3-3 of Fig. 2;

Fig. 4 is a view of a pole by means of which the mail carrier releases the latch and swings the box carrier towards him;

Fig. 5 is a fragmentary sectional view illustrating a modified form of latch.

The standard 1 which forms a portion of the mail box mounting is preferably a wooden post but may be formed of metal or any other suitable material. The standard is embedded in the ground at one side of a road and is of a suitable height. In order to pivotally mount the swinging box-carrying arm which is indicated in general by the numeral 2, there has been provided upper and lower brackets 3 and 4 which are secured to the post or standard 1, as shown in

Fig. 1. The upper bracket 3 is U-shaped and is formed from a strip of flat metal bent intermediate its length to provide a bridge portion 5 and side arms 6. The side arms are twisted, as shown at 7, so that their end portions 8 may rest flat upon the upper end of the post 1 where they are firmly secured by screws or other suitable fasteners 9. An auxiliary bracket 10, which is also formed from a strip of flat metal and substantially V-shaped in top plan, is disposed between the arms of the U-shaped bracket 3 with its head portion 11 projecting from the post and its arms overlapping the portions 8 of the arms 6 and firmly secured by screws or other suitable fasteners 12. It will thus be seen that the upper U-shaped bracket together with the auxiliary bracket will be very firmly anchored to the post with portions projecting transversely from the front of the post. The lower bracket 4, which is also formed of metal, is secured against the front of the post beneath the projected head portion 11 of the auxiliary bracket and is provided with a tongue 13 which projects outwardly and is formed with an opening 14 substantially aligned with an opening 15 in the head portion of the auxiliary bracket.

The box carrier 2 is formed from a metal rod which is preferably circular in cross section and bent intermediate its length to provide an upper horizontal bar 16 and depending brace 17. The ends of the bar 16 and brace 17 are bent to form depending pins 18 and 19 which are passed through the openings 15 and 14 to pivotally mount the box carrier. These depending pivot pins 18 and 19 are threaded and carry securing nuts 20 and 21 which serve to retain them in place and prevent accidental movement thereof out of the openings. Adjacent its outer end the upper horizontal bar 16 is flattened to provide seats 22 having openings formed therein to receive bolts or other suitable fasteners 23 by means of which cross bars 24 are held in place. These cross bars have their end portions formed with openings 25 to receive screws or other suitable fasteners by means of which a mail box of a suitable construction is to be secured. It will, of course, be obvious that additional cross bars 24 may be provided if an extra large box is to be supported. By having the box carrier pivotally mounted, it may be normally disposed at one side of the

road substantially parallel thereto where it will be out of the way. When, however, the mail carrier desires to place mail in the box or remove letters deposited therein for collection, he may swing the box carrier and box into a position at right angles to that shown in Fig. 1 and the box carrier will extend transversely of the road and project towards the automobile or other vehicle with the mail box disposed in such position that it may be readily reached by the mail carrier without leaving his vehicle.

It is desired to have the box carrier releasably held in the retracted or normal position so that it is not liable to be swung outwardly by wind, and in order to do so there has been provided a latch 26 which is formed from a short strip of metal and may be of the specific construction shown in Figs. 2 and 3 or formed as shown in Fig. 5. The strip from which the latch shown in Figs. 2 and 3 is formed is bent in spaced relation to its ends to form an intermediate portion 27 and offset upper and lower end portions 28 and 29 disposed above and below the cooperating arm 6 of the U-shaped bracket 3 when the latch is in a vertical position. A bolt 30 is passed through aligned openings formed in the latch and bracket arm and carries a spring 31 which is confined between the head of the bolt and outer face of the latch strip and serves to hold the latch strip in engagement with the bracket arm and yieldably resist turning of the latch about the bolt. The offset upper end portion of the latch is formed with a notch or recess 32 of sufficient depth to receive the upper bar 16 of the box carrier, as shown in Fig. 2, and from an inspection of this figure it will be readily seen that the latch will firmly hold the box carrier in the retracted or normal position and prevent it from being accidentally swung outwardly.

When the mail carrier desires to place mail in the box, a pole 33 which is carried in the vehicle is thrust outwardly and the depending lower end portion 29 of the latch engaged in the recess 34 between the prong 35 and hook 36 of the metal head 37 carried by the pole. A pushing action is then applied which will serve to swing the latch about the bolt until the latch is disposed at such an angle that the upper bar of the box carrier may be swung forwardly out of the recess or notch 32. The upper arm of the box carrier is then engaged by the hook 36 and the pole drawn upon to swing the box carrier into position where the box may be readily reached by the mail man. The mail to be collected is then removed from the box and mail to be delivered placed therein and the upper bar of the carrier or support 16 engaged in the recess 34 and a pushing action applied to return the box and support to the original position. When the box

carrier is returned to the original position, its upper arm moves into the recess 32 of the latch and causes the latch to be returned to the vertical position with its upper and lower end portions in overlapping and interlocking engagement with the upper and lower edges of the cooperating arm 6 of the bracket 3 and the support will be again securely but releasably held in the normal position.

The latch, which is shown in Fig. 5 and may be substituted for the latch shown in Figs. 2 and 3, is also formed from a short strip of metal and will have its upper and lower end portions projecting from the arm of the bracket 3 and its projected upper end portion formed with a notch or recess similar to the notch 32. The metal strip 38 from which this latch is formed has its side portions bent to form flanges 39 which project towards the arm of the bracket 3 and are adapted to fit into grooves 40 formed in the outer face of the arm 6 of the bracket. A bolt 41, similar to the bolt 30, is passed through aligned openings in the bracket arm and latch and carries a spring 42 which engages the outer face of the latch and forces it toward the bracket arm so that the flanges 39 will be firmly seated in the grooves 40. The side flanges will, therefore, be interlocked with the arm of the bracket 3 and the box carrier may be securely but releasably held in the normal position.

Having thus described the invention, I claim:

1. A device of the character described comprising a standard, a support, means carried by the standard and loosely engaged by the support to pivotally connect the support with said standard for movement in a horizontal plane, a bracket extending from said standard beneath a portion of said support to brace the support, and a latch movably connected with said bracket and adapted to be moved into and out of position to engage said support and releasably hold the support in a set position.

2. A device of the character described comprising a standard, a support, means carried by the standard and loosely engaged by the support to pivotally connect the support with said standard for movement in a horizontal plane, a bracket extending from said standard beneath a portion of said support to brace the support, and a latch pivotally connected with said bracket and yieldably interlocked therewith in position to engage said support and releasably secure the support in a set position.

3. A device of the character described comprising a standard, a support pivotally connected with said standard for movement in a horizontal plane, a bracket extending from said standard beneath a portion of said support, and a latch pivotally connected

with said bracket and yieldably held in engagement with a portion of a side face thereof and having a portion interlocking with the bracket to releasably hold the latch in 5 a vertical position with the support seated in a seat formed in the upper portion of the latch and held in a set position.

4. A device of the character described comprising a standard, upper and lower 10 brackets carried by said standard, an auxiliary bracket carried by said upper bracket, a support including a horizontal arm pivoted to said auxiliary bracket and a bracing arm pivoted to said lower bracket, the horizontal 15 arm extending across said upper bracket, and a latch carried by said upper bracket and adapted to engage the horizontal arm of said support to releasably hold the support in a set position.

20 5. A device of the character described comprising a standard, a U-shaped bracket carried by said standard and projecting transversely therefrom, an auxiliary bracket carried by the arms of said U-shaped 25 bracket and projecting from the standard, a bearing bracket carried by said standard beneath said U-shaped bracket, a support including a horizontal arm pivoted to said auxiliary bracket and extending from said 30 standard across said U-shaped bracket and a brace arm pivoted to said bearing bracket, and a latch carried by one arm of said U-shaped bracket and adapted to engage the horizontal arm of said support to releasably 35 hold the support in a set position.

6. A device of the character described comprising a standard, a U-shaped bracket carried by said standard and projecting transversely therefrom, an auxiliary bracket 40 carried by the arms of said U-shaped bracket and projecting from the standard, a bearing bracket carried by said standard beneath said U-shaped bracket, a support including a horizontal arm pivoted to said auxiliary bracket and extending from said 45 standard across said U-shaped bracket and a brace arm pivoted to said bearing bracket, a pin projecting outwardly from one arm of said U-shaped bracket, a latch to engage the horizontal arm of said support pivoted upon said pin and adapted to releasably hold the support in a set position, said latch having a recess to receive the horizontal arm of said 50 support and side flanges to fit into grooves formed in the arm of the U-shaped bracket and resist turning of the latch, and a spring upon said pin to yieldably retain the latch against movement with its flanges seated in the grooves.

In testimony whereof I affix my signature.

7. A device of the character described comprising a standard, a U-shaped bracket carried by said standard and projecting transversely therefrom, an auxiliary bracket carried by the arms of said U-shaped bracket and projecting from the standard, a bearing bracket carried by said standard beneath said U-shaped bracket, a support including a horizontal arm pivoted to said auxiliary bracket and extending from said standard across said U-shaped bracket and a brace arm pivoted to said bearing bracket, a pin projecting outwardly from one arm of said U-shaped bracket, a latch to engage the horizontal arm of said support pivoted upon said pin and adapted to releasably hold the support in a set position, said latch having a recess to receive the horizontal arm of said support and an offset portion to engage the arm of the U-shaped bracket and interlock therewith, and a spring upon said pin engaged with said latch to yieldably resist movement of the latch.

8. A device of the character described comprising a standard, a U-shaped bracket carried by said standard and projecting transversely therefrom, an auxiliary bracket carried by the arms of said U-shaped bracket and projecting from the standard, a bearing bracket carried by said standard beneath said U-shaped bracket, a support including a horizontal arm pivoted to said auxiliary bracket and extending from said standard across said U-shaped bracket and a brace arm pivoted to said bearing bracket, a pin projecting outwardly from one arm of said U-shaped bracket, a latch to engage the horizontal arm of said support pivoted upon said pin and adapted to releasably hold the support in a set position, said latch having a recess to receive the horizontal arm of said support and side flanges to fit into grooves formed in the arm of the U-shaped bracket and resist turning of the latch, and a spring upon said pin to yieldably retain the latch against movement with its flanges seated in the grooves.
